UNITED STATES PATENT OFFICE.

JAMES A. CONNELLY, OF HAMILTON, OHIO, ASSIGNOR OF ONE-HALF TO
GEORGE F. BLACK, OF HAMILTON, OHIO.

GUARD-BOARD FOR COUCH-ROLLS.

SPECIFICATION forming part of Letters Patent No. 700,133, dated May 13, 1902.

Application filed February 10, 1902. Serial No. 93,301. (No model.)

To all whom it may concern:

Be it known that I, JAMES A. CONNELLY, a citizen of the United States, residing at Hamilton, Butler county, Ohio, (post-office address care Black & Clawson Co., Hamilton, Ohio,) have invented certain new and useful Improvements in Guard-Boards for Couch-Rolls, of which the following is a specification.

The couch-roll of a paper-making machine is covered with a very expensive felt jacket and is continually washed by running water as it leaves the web of paper, the guard-board extending along the upper portion of the roll and bearing upon it and preventing the rearward flow of the wash-water and removing foreign matter from the felt. Much trouble has been experienced in securing the proper action of the guard-board without rapid wear of the felt jacket and many devices for the active edge of the guard-board have been experimented with, including rigid edges, flexible edges, wooden edges, edges formed of rubber, edges formed of laminations of dissimilar flexible materials, and edges formed by inflated flexible tubes.

My present invention relates to an improvement in guard-boards, which will be readily understood from the following description, taken in connection with the accompanying drawings, in which—

Figure 1 is a front elevation of a couch-roll provided with a guard-board exemplifying my invention; Fig. 2, a vertical transverse section of the same, and Fig. 3 a vertical transverse section at the active portion of the guard-board upon an enlarged scale.

In the drawings, 1 indicates an ordinary couch-roll; 2, its felt jacket; 3, a supporting-board extending along over the roll, to be rigidly supported after the manner of the usual guard-boards, this supporting-board being, if desired, the ordinary guard-board, but so supported as to have its usual lower edge free of the couch-roll; 4, the guard-board proper, the same being disposed against the face of the supporting-board 3, the guard-board 4 being formed, preferably, of wood, with its lower edge some distance above the couch-roll and preferably some distance above the lower edge of supporting-board 3; 5, a horizontal series of lag-screws passing through

vertical slots in guard-board 4 and screwing into supporting-board 3, the heads of these lag-screws, however, standing forward some distance from the front face of guard-board 4; 6, a series of hangers, one for each of the lag-screws 5, these hangers lying against the front face of guard-board 4 and extending upwardly beyond the upper edge of the same, the lower portion of each hanger engaging one of the lag-screws 5 between its head and the guard-board 4, the lag-screws thus serving to clamp the hangers against guard-board 4 and to clamp the latter snugly against supporting-board 3; 7, rearwardly-turned portions at the tops of the hangers 6, the same extending rearwardly and fitting against supporting-board 3 some distance above guard-board 4 and secured firmly to the supporting-board by screws; 8, set-screws screwing downwardly through the upper portions of the hangers 6 and having their lower ends engaging the upper edge of guard-board 4; 9, a metallic clamp-strip secured against the face of guard-board 4 at its lower edge and preferably rabbeted into the face of the guard-board, the lower edge of this strip projecting downwardly to near the couch-roll and some distance below the lower edge of guard-board 4; 10, a similar metallic clamp-strip similarly disposed at the rear face of guard-board 4, its rear face lying against the front face of supporting-board 3 and its lower edge projecting down below guard-board 4 and even with the lower edge of clamp-strip 9; 11, a thin groove or kerf extending into the lower edge of guard-board 4 and from end to end thereof and disposed with its rear wall near the front face of clamp-strip 10, so that the surface of the guard-board against which clamp-strip 10 rests is capable of forward flexation; 12, a horizontal series of studs secured, as by riveting, in clamp-strip 10 and projecting forwardly therefrom through suitable holes in guard-board 4 and front clamp-strip 9; 13, thumb-nuts on the forward ends of these studs; 14, several layers of felt, such as is employed for the jackets of couch-rolls, clamped between clamp-strips 9 and 10 and extending from the lower edge of guard-board 4 down to the felt jacket of the couch-roll, on which the lower edges of the felt layers 14 bear with adjusted

pressure, and 15 swivels secured to the upper edge of guard-board 4 and engaged by the lower ends of screws 8.

The strips of felt having been cut to proper dimension and in proper number to fill the space between clamp-plates 9 and 10 they may be clamped in place at the lower edge of the guard-board by tightening up thumb-nuts 13, the flexibility resulting from kerf 11 permitting the two clamp-plates to approach each other, and thus hold the felt layers in place on the guard-board. The lag-screws 5 hold the guard-board nicely against supporting-board 3, the guard-board being clamped with proper tightness between the supporting-board and the hangers 6. The guard-board may be adjusted vertically by means of screws 8, the multiplicity of these screws permitting of delicate adjustment of the active felt edge of the guard-board nicely to the felt jacket of the couch-roll in the original setting and in subsequent adjustment for wear. The felt layers 14 present to the felt jacket of the couch-roll the ends of a great number of vertical yarns forming the vertical elements in the woven layers of felt, the active edge of the guard-board thus acting upon the felt jacket with a delicate brush-like action, the result being a peculiarly satisfactory performance of the intended work of the guard-board along with a remarkably small amount of wear upon the expensive jacket of the couch-roll.

I claim as my invention—

- 35 1. In a guard-board for a couch-roll, the combination, substantially as set forth, of a board supported over the couch-roll, front and rear clamp-strips secured to the lower edge thereof, layers of felt clamped between said clamp-strips and extending from the lower edge of said board to the jacket of the couch-roll and presenting their lower edges to the latter, and means for vertically adjusting said board.
- 45 2. In a guard-board for a couch-roll, the combination, substantially as set forth, of a board supported over the couch-roll and having a kerf extending up into its lower edge

and along its length and near one of its surfaces, clamp-strips secured to the front and rear faces of said board and projecting below the lower edge of the board, flexible material disposed between said clamp-strips and extending from the lower edge of said board down to the jacket of the couch-roll, clamp-screws engaging said board and clamp-strips and crossing said kerf, and means for vertically adjusting said board.

3. In a guard-board for a couch-roll, the combination, substantially as set forth, of a supporting-board disposed over the couch-roll, a guard-board disposed against the front surface of said supporting-board and provided with an active edge engaging the jacket of the couch-roll, hangers lying against the front face of said guard-board and extending upwardly and then rearwardly over the upper edge of the guard-board, screws passing through the lower portions of said hangers and through vertical slots in said guard-board and into the supporting-board, and screws threaded downwardly through the upper portions of said hangers and engaging the upper edge of said guard-board.

4. In a guard-board for a couch-roll, the combination, substantially as set forth, of a supporting-board disposed over the couch-roll, a guard-board disposed against the front surface of said supporting-board and provided with an active edge engaging the jacket of the couch-roll, hangers lying against the front face of said guard-board and extending upwardly and then rearwardly over the upper edge of the guard-board and secured to said supporting-board, screws passing through the lower portions of said hangers and through vertical slots in said guard-board and into the supporting-board, and screws threaded downwardly through the upper portions of said hangers and engaging the upper edge of said guard-board.

JAMES A. CONNELLY.
